UNITED STATES PATENT OFFICE.

CHARLES P. STEINMETZ, OF SCHENECTADY, NEW YORK, ASSIGNOR TO GENERAL ELECTRIC COMPANY, A CORPORATION OF NEW YORK.

ELECTRIC LAMP.

1,092,083.

Specification of Letters Patent. Patented Mar. 31, 1914.

Application filed December 19, 1903. Serial No. 185,790.

To all whom it may concern:

Be it known that I, CHARLES P. STEINMETZ, a citizen of the United States, residing at Schenectady, in the county of Schenectady and State of New York, have invented certain new and useful Improvements in Electric Lamps, of which the following is a specification.

My present invention relates to the construction and operation of devices such as electric lamps, rectifiers, or the like, in which a vapor such as that of mercury inclosed in an otherwise exhausted envelop serves as the conducting medium through which the electric current is conveyed between electrodes located in the envelop. In these devices one of the electrodes, at least, is of vaporizable material. It has been found necessary to employ special devices to start the flow of current between the electrodes in these lamps.

My present invention has for one of its objects the provision of improved means to start the current flow from the vaporizable electrode.

A further object of my present invention is to obtain an advantageous construction and arrangement of the various parts which constitute a complete device of the character specified.

The various features of novelty which characterize my invention are pointed out with particularity in the claims appended to and forming a part of this specification.

For a better understanding of my invention, reference may be had to the accompanying drawings in which I have illustrated embodiments of my invention.

Figure 1 is a perspective view, and Fig. 2 is a sectional elevation illustrating one embodiment of my invention; Fig. 3 is a partial sectional elevation showing a modification; and Fig. 4 is a view similar to Fig. 3 showing another modification.

Referring particularly to Figs. 1 and 2 of the drawings, 1 represents the envelop of an exhausted chamber in which the vapor conductor is located. The envelop may be cylindrical in general outline and is preferably formed with an enlargement 2 at its upper end and an enlargement 3 near its lower end. Below the enlargement 3 the tube is reduced somewhat in diameter. This envelop may be formed of glass and is of course transparent if the device is intended to operate as a

lamp, as in the construction illustrated. A terminal conductor 4 passes through the upper end of the envelop 1 and carries at its inner end an electrode 5 which may be formed of artificial graphite, iron or the like. 60 The electrode 5 is located below the body of the enlargement 2 which serves as a condensing chamber. The portion of the conductor 4 which extends between the electrode 5 and the wall of the envelop is surrounded by a non-conducting jacket 6 which may also be formed of glass. From the lower end of the electrode 5 a conducting filament 7, which may be formed of carbon, extends toward the other electrode. Suitable guides 8 which may be of glass project inwardly from the envelop and have apertures formed in their inner ends through which the filament 7 passes. These guides serve to hold the filament in a central position with reference to the wall of the envelop. In the lower end of the envelop is located a mass of fluid vaporizable material such as mercury 9 which forms one of the main electrodes of the lamp. A terminal conductor 10 passes through the lower portions of the envelop into the mercury 9. A member or plunger 11 normally floats in the mercury. The member 11, which is formed of magnetic material such as iron, comprises two cylindrical portions 12 and 13 of a diameter which allows them to slide freely in the reduced lower end of the envelop 1, and these portions are connected by an intermediate portion 14 of reduced diameter. 80 The lower reduced portion of the tube 1 is indented intermediate its ends to form stops 15 located between the enlarged portions 12 and 13. These stops limit the movements of the member 11. When the member 11 floats freely in the mercury, the stops 15 allow the portion 12 to project above the surface of the mercury, as shown in Fig. 2. When the member 11 is urged toward the bottom of the envelop in the manner hereinafter described, the stops 15 prevent the lower end of the member 12 from impinging against the lower end of the envelop 1. A cup-like depression or chamber normally filled with mercury 16 is formed in the upper end of the member 11. When the member 11 is in the position shown in Fig. 2 the lower end of the filament 7 dips into the mercury 16 carried in the cup located in the upper end of the member 11. The lower end of the en- 100 105 110

velop 1 passes through apertures formed in the end plates 17 of a solenoid magnet 18. The end plates 17 are secured by means of screws to a cylindrical non-magnetic shell or 5 a spool 19 upon which the winding 20 of the solenoid is wound. A cylindrical member 21 formed out of magnetic material and provided with a number of ventilating apertures 21' surrounds the winding 20 and is 10 secured to the end plates 17. This cylindrical member forms part of the magnetic circuit of the solenoid and is of assistance in obtaining the proper strength and disposition of the magnetic field produced by the 15 winding 20. Binding posts 22 and 23 are secured in any suitable manner to the under side of the lower end plate 17. The ends of a pair of rods 24 pass transversely through passages formed for the purposes in the 20 binding posts 22 and 23 to which they are detachably secured. The bodies of the rods 24, which are at right angles to the ends, extend parallel to the envelop 1, and their upper ends pass through a concave reflector 25 member 25 arranged to direct downward some of the light emanating from within the exhausted envelop. The reflector 25 closes the lower end of an inverted cup-shaped hood 26 preferably formed out of 30 sheet metal. An inverted U-shaped member 27, through the ends of which rods 24 pass, is clamped against the upper side of the reflector 25 by nuts which are screwed on the ends of the rods 24 above the ends of the 35 member 27 and below the reflector 25. The U-shaped member 27 is secured to the hood 26 by means of a bolt 28 and a nut 29. The bolt 28 may be extended to form a hook or the like by which the device may be secured 40 to a suitable support. An annular member 30 formed of some suitable refractory material such as soapstone is located within the hood. Suitable resistance conductors 31 and 32 are located in annular grooves formed for 45 the purpose in the upper surface of the member 30. One terminal of the resistance conductors 31 and 32 which may be connected in series, is connected to the inner end of a binding post 33 carried on the upper side of the hood 26. The other end of the resistance conductors 31 and 32 is grounded to the metal hood which is electrically connected with the lower end plate 50 of the solenoid coil 18 through the reflector member 25 and rods 24. One terminal of the winding 20 is in electrical connection with the end plate 17. The other terminal 34 of the winding 20 is connected to the terminal conductor 10. The terminal conductor 4 is connected through a conductor 36 to a binding post 35 carried by the hood 26. Spring clips 24' are carried by the rods 24. These clips serve to position the upper end 60 of the envelop 1. When it is desired to remove the envelop from the lamp structure, 65

the set screws which secure the ends of the rods to the binding posts are turned to release the rod ends after which the coil may be turned on them to swing the upper end of the envelop clear of the lamp top. When 70 the plunger or member 11 is in the position shown in Fig. 2, which represents the out-of-service condition of the lamp, a circuit is established between the electrodes 9 and 5 by means of the filament 7, mercury 16, and 75 member 12. Upon connecting the binding posts 33 and 35 in a suitable electric circuit, current will begin to flow from the binding post 35 through the conductor 36, terminal conductor 4, terminal 5, filament 7, mercury 80 16, member 11, mercury electrode 9, terminal conductor 10, terminal 34, winding 20, rods 24, reflector 25, hood 26, resistance conductors 31 and 32 to the binding post 33. The passage of current through the winding 85 20 will cause the member 11 to be totally submerged beneath the surface of mercury 9. When the surface of the mercury 16 in the plunger 11 leaves the end of the filament 7 an arc will be formed between the filament 90 and the mercury in the cup. This arc will be continued after the member is entirely submerged in which case it will extend from the surface of the main body of mercury with which the mercury 16 is now united. 95 The formation of this arc will cause the envelop 1 to be filled with conducting vapor, whereupon the current will desert the filament 7 and will flow between the electrode 5 and the surface of the mercury 9 through 100 the conducting vapor. When for any reason the circuit through the coil 20 is interrupted, as by throwing the lamp out of service, the member 11 will immediately return to the position shown in Fig. 2 by reason of 105 its buoyancy and the end of the filament 7 will again project into the mercury carried in the upper end of the member 11. The resistance conductors 31 and 32 form a regulating resistance for the lamp. More or less 110 of these conductors may be included in the lamp circuit according to the circumstances of use and in some cases they may be dispensed with entirely. The enlargement 3 of the envelop is so located that the submergence of the member 11 produces but a slight 115 change in the level of the mercury 9 which extends into it. In the form of my invention shown in Fig. 3 the member 11 is in the form of a glass tube, the lower end of the tube being closed and enlarged as indicated at 37. A mass of 120 magnetic material 38, which may consist of a bundle of iron wires, is placed in the lower end of the tube. A partition or diaphragm 39 closes the tube above the magnetic material thus forming a closed and hermetically sealed chamber 40 in which the magnetic material is located and leaving a cup or recess 41 above the diaphragm which is 125 130

filled with mercury 42. A terminal conductor 43 passes through the diaphragm 39. Another terminal 44 projects through the lower end of the tube. The conductors 43 and 44 which are electrically connected with one another, are preferably formed of platinum and in fact may consist of an integral piece of platinum wire. A quantity of mercury 45 substantially fills the space in the chamber 40 unoccupied by the wires forming the magnetic material 38. It will, of course, be understood that the mercury in the chamber should not entirely fill it so that the expansion taking place when the tube is heated will not cause the mercury to break the tube. It is not essential that all air be removed from this chamber but the chamber should preferably be heated at the time of sealing. As shown in Fig. 3 the enlargement 37 of the member 11 plays in an enlargement 46 of the envelop. The engagement of the enlargement 37 with the upper end of the enlargement 46 serves to limit the upward movement of the member 11. At the lower end of the enlargement 46 a small pocket 47 is formed into which the tip of the member 11 and projecting conductor 44 extend when the member 11 is submerged. This prevents the tip and the conductor from impinging against the wall of the envelop. A winding 20', similar to the winding 20, is placed around the lower end of the envelop 1. The operation of this form of my invention is practically identical with that of the form shown in Figs. 1 and 2.

The enlargement 3' of the envelop 1, shown in Figs. 3 and 4 and corresponding in position to the enlargement 3 of the form shown in Figs. 1 and 2, forms a very good condensing chamber. The extension 3" in line with the body of the envelop serves to steady the arc and improve the operation of the condensing chamber formed by the enlargement. With this construction the condensing chamber formed by the enlargement 2 at the extreme upper end of the envelop may be dispensed with if desired. The extension 3" forms an annular lip around the upper portion of the interior of the condensing chamber 3', and intercepts the flow of mercury from its normal position in case the lamp is accidentally inverted during transportation.

In order that the member 11 should not have too close a fit in the lower end of the envelop, an annular ridge 48 may be formed about the glass covering of the member 11 as shown in Fig. 3. This assists in centralizing the floating member 11 while at the same time preventing the body of the member 11 from coming in contact with the inner wall of the envelop 1 and sticking thereto.

In the form of my invention shown in

Fig. 4 the lower end of the filament 7 is secured to a block 49 of carbon, graphite or the like which is carried by a glass arm or support 50 similar to the guides 8. The block may serve as a stop to limit the upward movement of the plunger 11 thus doing away with the enlargements 37 and 46 of the member 11 and envelop respectively shown in Fig. 3. In this form the lower end of the filament 7 is firmly anchored in place and a strong mechanical arrangement is obtained.

What I claim as new and desire to secure by Letters Patent of the United States, is,—

1. In combination, an exhausted envelop, a non-vaporizable electrode, a fluid vaporizable electrode, a member in said fluid electrode, said member being provided with a recess or receptacle, a second body of vaporizable fluid in said recess or receptacle, means for causing an arc to be started between the non-vaporizable electrode and the fluid contained in said recess or receptacle, and means for causing said member to be submerged in said fluid vaporizable electrode. 99

2. The combination of an exhausted envelop, two bodies of vaporizable material therein, said bodies being initially separate but electrically connected within the envelop, and means for starting an arc from one of said bodies by relatively moving said bodies. 95

3. In a vapor electric device, the combination of an envelop, a mass of vaporizable material located at one end thereof but out of contact therewith, means for changing the level of said vaporizable material and means coöperating with said vaporizable material to start an arc. 100

4. The combination of an exhausted envelop having an enlargement at one end, a fluid electrode located at that end of the envelop, a plunger having an enlarged end located within the enlarged end of said envelop, a stop for limiting the movement of said plunger and means for moving said plunger. 110

5. In combination, an exhausted envelop, a fluid electrode, a conducting filament adjacent thereto, an arc-starting plunger floating in said fluid electrode and carrying means initially engaging said filament, and means for moving said engaging means out of engagement with said filament. 115

6. In combination, an exhausted envelop, a fluid electrode, a conductor in fixed relation to said envelop, and means floating in said fluid electrode and movable with respect to said envelop for initially connecting said conductor and said electrode. 125

7. In combination, an exhausted envelop of rigid material, a fixed conductor, a member in said envelop carrying a movable body of vaporizable material initially in contact 130

- with said conductor, and means for moving said member to cause said body of vaporizable material to move out of contact with said conductor.
5. 8. In a vapor electric apparatus, a stationary evacuated envelop, a solid conductor fixed therein, a movable body of vaporizable material in said envelop and initially in contact with said conductor, and 10 means responsive to flow of current through said apparatus for moving said body of vaporizable material out of contact with said conductor to initiate an arc in said envelop.
15. 9. In a vapor electric apparatus, the combination of an exhausted envelop, a body of fluid conducting material therein, a member in said body having a fluid-containing pocket or chamber, means for moving said 20 member so that fluid in said pocket or chamber will be united with said fluid body and means coöperating with the fluid in said pocket to start an arc.
25. 10. In a vapor electric apparatus, the combination of an exhausted envelop, a fluid electrode contained therein, an arc-starting device, and means for submerging one member of said arc-starting device in said fluid electrode.
30. 11. In combination, an exhausted envelop, a mass of vaporizable material located in said envelop, a second mass of vaporizable material located in said envelop, a non-vaporizable conducting body located in said 35 envelop normally in contact with said second body of vaporizable material, and means for separating said non-vaporizable conductor from said second body of vaporizable material, to form an arc.
40. 12. The combination of an exhausted envelop, an electrode and two bodies of vaporizable material therein, means for moving one of said bodies until it unites with the other body, and means for starting an arc 45 during this movement.
13. In combination, an exhausted envelop, a main body of vaporizable material and an auxiliary body of vaporizable material separated therefrom, and means for 50 starting an arc from said auxiliary body as a cathode and for transferring said arc to said main body.
55. 14. In combination, an exhausted envelop, two bodies of vaporizable material, an electrode, and means for starting an arc between one of said bodies of vaporizable material and said electrode and for transferring the arc from the one of said bodies to the other of said bodies.
60. 15. In combination, an exhausted envelop, a conducting filament, an electrode of fluid vaporizable material, an arc-starting plun- 65 ger floating in said electrode, and means for moving said plunger away from the end of said filament to establish an arc thereto. 70
16. In combination, an exhausted envelop, a conducting filament therein, an electrode of fluid vaporizable material, and an arc-starting float having means initially establishing electrical connection with said filament and movable in line with said filament. 75
17. In a vapor electric apparatus, a float provided with a pocket and having its outer surface insulated, and a conductor extending from the pocket to the lower end of the float. 80
18. In a vapor lamp structure, a top member, a magnetizing coil pivotally supported therefrom, and an exhausted envelop supported in said magnetizing coil and containing arc starting means with which said magnetizing coil may co-act. 85
19. In a vapor lamp structure, a top member, a magnetizing coil supported therefrom, and an exhausted envelop supported in said magnetizing coil and containing arc starting means with which said magnetizing coil may coact, the top of said envelop being movable sidewise to clear said top member 90 when the envelop is to be removed from the coil. 95
20. In a vapor lamp structure, a supporting member, a member extending therefrom, a magnetizing coil pivotally connected thereto, and an exhausted envelop supported by the coil. 100
21. In a vapor lamp structure, a reflector, a magnetizing coil supported therefrom, and an exhausted envelop supported by said coil and extending toward said reflector, said envelop containing a movable magnetizable member with which said coil may coact. 105
22. In a vapor lamp structure, a supporting member, a member extending therefrom, a magnetizing coil pivotally connected thereto, and an exhausted envelop supported by the coil. 110
23. The combination of an exhausted envelop, a fluid electrode therein, a conducting filament adjacent to said electrode, an arc-starting plunger floating in said fluid electrode and initially providing a path for current through said filament, and means for moving said plunger to change the nature 115 of said path.
- In witness whereof, I have hereunto set my hand this 15th day of December, 1903.
